UNITED STATES PATENT OFFICE.

CHARLES GUSTAFSON, OF ST. PAUL, MINNESOTA.

INDICATING APPARATUS.

1,195,355.

Specification of Letters Patent. Patented Aug. 22, 1916.

Application filed April 23, 1915. Serial No. 23,433.

To all whom it may concern:

Be it known that I, CHARLES GUSTAFSON, a citizen of the United States, residing at St. Paul, in the county of Ramsey and State 5 of Minnesota, have invented certain new and useful Improvements in Indicating Apparatus, of which the following is a specification.

My invention relates to improvements in 10 indicating apparatus, its object being particularly to provide an apparatus to be carried by a car indicating the stops to the passengers, said apparatus being electrically actuated in the travel of the car.

15 To this end the invention consists in the features of construction and combination hereinafter particularly described and claimed.

In the accompanying drawings forming 20 part of the specification, Figure 1 represents a front elevation of my improved indicating apparatus; Fig. 2 is a side elevation with the outer plate of the containing casing removed. Fig. 3 is a detail view of 25 a portion of a trolley wire and trolley pole indicating a portion of the operating mechanism; Fig. 4 is a view opposite to Fig. 2; and Fig. 5 is a side elevation of a slightly modified construction with part of the containing casing removed to illustrate the 30 modification.

Referring to the drawings, A represents a containing casing for the indicating mechanism and associated means therefor, said 35 casing being adapted to be suitably supported at a proper position in the car to indicate the desired display matter, as the names of the stops, to the passengers. The indicating portion of the apparatus supported within the casing consists of a carrying roll 2 having journal support 3 in a bracket 4 secured as by rivets 5 upon the bottom of the casing, and a similar roll 6 having journal support 7 in a bracket 9, 40 said bracket being secured as by rivets 10 to the top of the casing. A driving roll 11 is mounted upon the shaft 12 intermediate of the carrying rolls. An indicating sheet 13 extends from one carrying roller to the other, intermediately running around the power roll and over idler rollers 14 and 15 arranged between the roll 2 and the power roll and between the roll 6 and the power roll. Thus, it will be evident, by referring 45 to Fig. 2, that the portion of the indicating sheet standing between the idler rollers

14 and 15 will be in perpendicular position behind the transparent sight pane 16.

For the purpose of imparting a step by step movement to the power roll to successively bring the different designations upon the indicating sheet into view, I provide the following described actuating mechanism. Rotatably supported upon the shaft 12 is an upwardly extending arm 17. 50 The arm 17 has central pivotal connection 18 with a horizontal bar 19, the bar 19 at its opposite ends being pivotally connected to the armatures 20 and 21, respectively, in sliding position in connection with the magnets 22 and 23, respectively. The free end of the lever arm 17 has pivotal connection 24 centrally with transverse bars 25 and 25^a. The bars 25 and 25^a at their ends have spring connections 26 and 26^a with the 55 bracket 9. Having fulcrum support 27 and 28 on the bars 25 and 25^a at points between the inner sides of the springs 26 and 26^a are lever arms 29 and 30. The lever arms 29 and 30 at their lower ends are pivotally 60 connected respectively with the armatures 31 and 32 slidably arranged in connection with the electromagnets 33 and 34. The lever arms 29 and 30 are formed at their upper free ends with the fixed dogs 35 and 36, respectively, and pivotally supported alongside said dogs 35 and 36 are the dogs 37 and 38, respectively.

Fixedly mounted upon a shaft 39 intermediate of the roll 6 and the power roll is 65 a notched disk 40 and behind the same a pair of toothed disks 41 and 42, a spur wheel 43 being secured upon the shaft behind the toothed disk 42. The spur wheel 43 engages with a pinion 44 mounted upon the shaft 12 70 of the power roll, whereby the rotation of the spur wheel 43, as hereinafter described, will rotate the shaft 12 and the supported power roll. The shaft 12 supports the ratchet wheel 45, in connection with the opposite sides of which work spring pressed pawls 46 and 47. The lever arm 17 at its lower end carries a lug 48 to engage with one or the other of said pawls, as the arm 17 is turned, so that one of the spring 75 pressed pawls will normally stand in engagement with the ratchet wheel to hold the shaft of the power roll from turning beyond the amount turned by the spur wheel. The rollers 2 and 6 are held under spring tension 80 by means of springs 49 and 50, each being connected at one end with a spur wheel

51 and having pinion connection 52 with the shaft of the adjacent supply roll.

The dogs 35 to 38 are so positioned that when the bars 25 and 25^a are moved to the left, as shown in Fig. 2, the dog 38 will fit into the serrations of the disk 40 and the dog 36 will engage with the teeth of the disk 41. The spring pressed dogs 37 and 38 simply act as locking dogs to hold the shaft 39 from forward movement beyond the point where the shaft is rotated by the dogs 35 and 36. When the bars 25 and 25^a in the operation of the apparatus are moved to the right, the dogs 36 and 38 will be released and the dog 37 will be carried into the serrations of the disk 40.

For the purpose of bringing about a reverse movement of the indicating sheet, as hereinafter particularly described, I provide a vertically disposed arm 53 having central fulcrum support 54. The upper free end of the lever arm 53 stands alongside the indicating sheet. The lower end of the arm 53 has sliding connection with the upper end of a lever 55, the lever 55 having central fulcrum support 56. The lower end of the lever 55 has pivotal connection 57 with a lever arm 58. The free end of the lever arm 58 stands alongside of the indicating sheet, the lever arm centrally resting upon an extension 59 of the bracket 4. The end of the indicating sheet adjacent to the roll 2 carries a lug 60 for the purpose of engaging with and actuating the lever 58, as hereinafter pointed out, to bring about reversing of the apparatus, as the unwinding of the sheet from the roll 2 and winding up upon the roll 6 is completed. There is also a similar lug 60^a carried by the opposite end of the sheet to engage with the end of the lever 53 and actuate the same when the sheet is oppositely wound up upon the roller 2.

For the purpose of bringing the electric current from the overhead trolley wire B to the electromagnets I provide the following combination of parts. Depending from the trolley wire B at predetermined points are the contacts 61 which as the trolley wheel 62 passes, will brush the contact 63 supported by the trolley pole 64. A conducting wire 65 leads from the contact 63 through the casting to the magnet 23, the electromagnets 23 and 33 being in circuit. The electromagnet 22 is electrically connected with the electromagnet 34 through the wiring 68 and 70. Arranged in connection with the lever arm 53 are the jack knife switch members 71 and 72, which are electrically connected with the electromagnets 22 and 34. Similar jack knife switch members 73 and 74 are electrically connected with the electromagnets 23 and 33. The wiring is grounded through the ground wire 75.

In operation, as the sheet becomes un-
65 wound from the roll 2 to the roll 6, the stop

60 will strike the lever arm 58 and throw the switch members 73 and 74 into contact. As soon thereafter as contact is made between the contacts 61 and 63, the magnets 23 and 33 will be energized to move the dog 70 75 36 out and the dog 35 into contact with the corresponding toothed wheel through the medium of the magnet 23, the magnet 33 imparting a step by step movement to the ratchet wheel 43 to correspondingly move 75 the indicating sheet. When the opposite end of the line is reached the lug 60^a at the other end of the sheet will strike the lever arm 53 and by closing the switch members 73 and 72 and opening switch members 73 80 and 74 bring about the reverse travel of the sheet.

The modification shown in Fig. 5 is designed to be used in connection with a railway loop where the cars continue to go in 85 the same direction and where at the end of the loop, instead of reversing the direction of travel of the indicating sheet, it is necessary to rewind the sheet so that it may be again fed from the feed to the receiving 90 roll during the next trip around the loop. In the form shown in Fig. 5 the construction is just exactly like that shown in Fig. 2, with the exception that the electromagnet 33 is left out, inasmuch as it is only necessary to use the electromagnet 34 to impart step by step movement to the sheet actuating parts in one direction. When, in the modified construction, the car reaches the end of the loop, and the sheet becomes unwound, 95 the stop 60 carried by the sheet actuates the lever arm 58, and through the action of the magnet 23 carries the actuating dog out of engagement with the toothed disk and brings the contact members 76 and 77 into contact. 100 As will be noticed by referring to Fig. 5, the contact member 77 is fixed, and the contact member 76 is carried by the 105 110 115 120 125 130 135 140 145 150 155 160 165 170 175 180 185 190 195 198 200 205 210 215 220 225 230 235 240 245 250 255 260 265 270 275 having its armature directly connected to the opposite end of the lever arm for reciprocating it, a swinging support to which the lever arm is pivoted between its ends, 5 and magnetic means operable to swing the support for rendering the dog inoperative.

2. In an indicating apparatus of the character described, an indicating sheet, means supporting the same for movement, a power 10 roll for operating the sheet, a shaft supporting a roll, a pair of electro-magnetic devices having armatures, a bar connecting the armatures to be reciprocated thereby, an arm pivoted to the shaft and the bar, 15 means for driving the power roll including a rotatable ratchet, a bar pivoted to the arm at one end, a spring supporting the other end of the last bar, a dog supported by the last bar for engaging with the ratchet, a 20 magnet having its armature connected with the last bar for actuating the dog, and means for energizing the magnet and electro-magnetic devices.

3. In an apparatus of the character described, an indicating sheet, means supporting the same for movement, a power roll for operating the sheet, a shaft supporting the roll, a ratchet on the shaft, a pawl adapted for engaging the ratchet, an arm 25 ranged to disengage the pawl from the

ratchet, means for driving the power roll including a ratchet, a dog reciprocally supported for engaging with and operating the last ratchet and operatively connected with the arm, and means for rocking the arm to 35 thereby render the dog and pawl inoperative.

4. In an apparatus of the character described, indicating means, a power roll having a ratchet part, a pawl arranged to engage the ratchet part for holding the latter 40 against reverse rotation, means for rotating the power roll including a ratchet, an arm pivoted between its ends and having one end disposed to disengage the pawl from the ratchet part, a bar pivoted at 45 its inner end to the opposite end portion of the arm, a spring supporting the other end of the bar, a pivoted dog supported by the bar for engaging and operating the ratchet, electro-magnetic means for 50 moving the dog against the action of the spring, and other means connected to the arm for swinging the same to render the dog inoperative.

In testimony whereof I affix my signature 55 in presence of two witnesses.

CHARLES GUSTAFSON.
